UNITED STATES PATENT OFFICE.

PHILIP STRONG, JR., OF SARANAC, MICHIGAN, ASSIGNOR TO HIMSELF AND JEROME BROWN, OF SAME PLACE.

ARM-SEEDER.

SPECIFICATION forming part of Letters Patent No. 244,833, dated July 26, 1881.

Application filed June 4, 1881. (No model.)

To all whom it may concern:

Be it known that I, PHILIP STRONG, Jr., of Saranac, in the county of Ionia and State of Michigan, have invented a new and Improved 5 Arm-Seeder, of which the following is a full, clear, and exact description.

The object of my invention is the production of a device to be carried or worn by the person using it, by means of which all kinds of 10 grain or seed may be scattered or sown broadcast over the ground evenly and with less exertion than heretofore; and the invention consists, principally, of a bag having a flexible tube or smaller portion connected to a sec- 15 tional metal distributer, which is provided with a valve, and adapted to be swung from side to side for throwing and scattering the grain, the supply of grain from the bag being regulated by means of the valve.

20 The invention also consists in the construction and arrangement of the parts, as herein-after fully described.

In the accompanying drawings, Figure 1 is a perspective view of my invention, representing it as it appears when in position for use. 25 Fig. 2 is a longitudinal section of the distributer. Fig. 3 is a cross section of the distributer, taken on the line xx of Fig. 2. Fig. 4 is an end view of the distributer. Fig. 5 is a de- 30 tail showing one of the valves removed from the distributer; and Fig. 6 is a side elevation of a modified form of the distributer.

Similar letters of reference indicate corresponding parts.

35 A represents the bag, which is provided with a strap to rest upon the shoulder of the person; and B represents the distributer. The bottom of the bag is contracted into a small tube or sleeve-like portion, a , (or it may be pro- 40 vided with a flexible pipe,) which is secured around the end of the distributer, as shown.

The distributer is preferably formed of tin or other sheet metal, and in two sections, b and b' , which sections are united by the bayonet-joint 45 s' or similar means. Within the section b' is secured the annular ring c , to which is pivoted by the bolt and nut c' the eccentrically-perforated circular plates d and d' , which constitute the valve, and the plates d and d' are provided at 50 their lower edges with the lugs e and e' , by means of which the amount of coincidence of the openings through the plates is regulated, thus

adapting the device for grains of different size and for regulating the flow thereof from the bag. The outer end of the section b is flattened, so as to form the long but narrow mouth b'' , as shown clearly in Fig. 4.

55 Instead of making the distributer straight, as shown in Figs. 1 and 2, the same may be bent at an angle, as shown in Fig. 6, in which case the section b should be formed with the elbow f , for giving the section the desired slant.

60 The valve in the distributer might be omitted, the supply of grain being regulated by the hand of the operator grasping the flexible pipe or sleeve of the bag.

65 In use, the valves being set to suit the grain being sown, the bag filled with the grain is placed over the shoulder, and as the person 70 walks over the ground the distributer is to be swung alternately from side to side with sufficient force to throw the grain a suitable distance out of the distributer. The flow of the grain being regulated by the valves, and the 75 alternate swing of the distributer being regulated to the gait of the user, the grain will always be scattered evenly throughout the whole field, and with less trouble than heretofore.

80 Having thus described my invention, what I claim as new, and desire to secure by Letters Patent, is—

1. The flattened section b , in combination with the section b' attached to the bag and provided with the eccentrically-perforated and pivoted plates d and d' , as and for the purpose described.

2. The flattened section b , formed with the elbow f , in combination with the valved section b' and the supply-bag, as and for the purpose specified.

3. The arm-seeder made substantially as herein described, consisting of the sections b and b' and the bag A , the section b' being attached to the sleeve a of the bag A , and provided with the valve-plates d and d' , and the section b being flattened to form the long but narrow mouth b'' , as and for the purposes specified.

PHILIP STRONG, JR.
